By

J. Roy
A. St. John, attorney

UNITED STATES PATENT OFFICE.

JOSEPH ROY, OF CLEVELAND, OHIO, ASSIGNOR TO AMERICAN STOVE COMPANY, OF ST. LOUIS, MISSOURI, A CORPORATION OF NEW JERSEY.

STOVE-DOOR.

1,315,039.

Specification of Letters Patent.

Patented Sept. 2, 1919.

Application filed July 7, 1919. Serial No. 309,166.

To all whom it may concern:

Be it known that I, JOSEPH ROY, a citizen of the United States, residing at Cleveland, in the county of Cuyahoga and State of Ohio, have invented certain new and useful Improvements in Stove-Doors, of which the following is a specification, reference being had therein to the accompanying drawing.

This invention relates to improvements in stove doors, and is especially intended for use on gas ranges for the oven and broiler compartments.

It is also more particularly intended to be used for that form of door referred to in the trade as "drop doors," and its construction is particularly adapted for that use on account of being light and not requiring counter-balancing which is common in drop doors.

20 The object of my invention is to provide a stove door having the novel constructions hereinafter shown and described, whereby it is adapted to carry out the functions and purposes which will be hereinafter set forth.

25 In the accompanying drawings—

Figure 1 is a perspective view of my improved door, showing it in position on the oven of a gas stove.

30 Fig. 2 is a horizontal sectional view through the door just above its lower edge.

Fig. 3 is a vertical central sectional view.

Fig. 4 is a perspective view of portions of the three parts, comprising the door, the parts shown in separated relation.

35 Fig. 5 is a detached perspective view of the surrounding angle iron frame.

Fig. 6 is an inside elevation of the door.

Fig. 7 is a view of one of the pivot pins.

40 My improved door is essentially composed of three parts. An angle iron frame 1, and two telescoping sheet iron members 3 and 4. The angle iron frame 1 is L-shaped in cross-section. The flange *a* of the angle iron, for convenience, will be termed a longitudinally extending flange, because it extends in the plane of the door, and the flange *b* will be termed a transverse flange, because it extends in a direction transverse the plane of the door. 5 is the oven frame to which the door is applied, and the door, as illustrated in Fig. 1, is arranged as a "drop door."

45 The angle iron frame 1 is bent into a U-shape contour, as shown in Fig. 5, and the bending of this angle iron stretches the longitudinally extending flange *a* at its corners

6, and makes the flange narrower at these points, as shown at *c*. The ends of the transverse flange *b* is cut off so that the ends of the flange *a* extend beyond the ends of the flange *b*, a distance sufficient to make the 60 doubled ends 7. These doubled ends 7 are rolled around and tightly embrace the pivot pins 8, and the overlapping portions of the doubled ends 7 are secured together in any suitable manner and, preferably, by the well-known spot welding, which acts and serves the purpose of rivets. These elongated doubled ends 7 form a reinforcement when the door is lowered and resting on the lugs 65 9 of the hinges 10.

70 The sheet-iron members 3 and 4 are each provided with peripheral inwardly extending flanges *d*, *e*, and the members telescoping each other, as shown in Figs. 2 and 3, forming a hollow panel A for the door. 75 These members 3 and 4, after being telescoped, are secured within the frame 1, by passing the bolts 11 through registering openings 12, 13 and 14 of the flanges *b*, *d* and *e*, and by passing bolts 13 through openings 80 14 at the ends of the flange *b* and through registering openings in the flanges *d* and *e* of the members 3 and 4.

75 The longitudinally extending flange *a* serves as an overlapping edge for the openings in the oven frame 5 and the lower edge of the outside member 3 has an inwardly extending L-shaped portion 15, which overlaps the cross strip 16, at the lower edge of the oven door frame 5. From this it will be observed that the longitudinal flange *a* and the depending L-shaped portion 15 furnish the door with an overlapping portion extending entirely therearound when the door is closed.

85 For the purpose of enabling the bolts 11 to be applied, the inner member 4 of the panel A is provided with openings 17, through which the nuts 11' of the bolts may be applied. For the same purpose the end of the flange *e* of the panel member 4 is cut 90 away as shown at *f*, and the L-shaped portion 15 is cut away as at *g* to permit access within the panel A, for applying the nuts 13' of the bolt 13.

95 A suitable handle 18 is attached to the flange *a* of the angle iron 1, and a suitable spring catch 19 projects from the oven frame 5 to engage the edge of the flange *a* to hold the door in its closed position.

100 A door having the foregoing construction.

is light and when used as a drop door does not require any counter-balancing and yet it is strong in construction.

While the door is especially intended for 5 a drop door, it is capable of being used as a vertical or swinging door.

Having thus described my invention, what I claim and desire to secure by Letters Patent is:

- 10 1. A stove door comprising a panel, a surrounding angle-iron frame having a U-shaped contour, one flange of the angle-iron extended and doubled backward and embracing hinge pins.
- 15 2. A stove door comprising a panel, an L-shaped angle-iron frame surrounding the panel and having longitudinal and transverse flanges, the angle-iron bent into a U-shaped contour, the ends of the longitudinal flange extending and doubled back into elongated doubled portions embracing between their ends hinge pins, the double portions serving as reinforcements to abut against stop lugs.
- 20 3. A stove door comprising a panel made up of two sheet members with inwardly telescoping flanges forming a hollow panel, an angle-iron frame bent into a U-shaped contour around the hollow panel, the flanges of the panels and the angle-iron secured together, and the ends of the angle iron provided with hinge members.
- 25 4. A stove door made up of a panel which consists of two sheet members with inwardly extending telescoping flanges, an L-shaped angle iron bent into U-shaped contour around

the panel, the angle-iron having longitudinal and transverse flanges, the flanges of the panel members and the transverse flange of the angle-iron secured together, the ends of the longitudinal flange of the angle iron extended and doubled backward to form hinge members and stop lug reinforcements.

5. A stove door comprising a panel made up of inner and outer sheet members having their sides and tops provided with inwardly extending flanges, and the bottom of the outside member provided with an inwardly and upwardly extending L-shaped portion for the purpose described, the said panel members having their side and top flanges telescoping, and an angle iron bent in U-shaped contour around the top and sides of the panel, the ends of the angle iron provided with hinge members.

6. A stove door comprising a panel made up of two members having inwardly extending telescoping flanges, an L-shaped angle iron bent around the panel in a U-shaped contour, the angle iron having longitudinal and transverse flanges, the transverse flange of the angle iron and the flanges of the panel members having registering bolt receiving openings, bolts passing through the openings, one of the panel members having openings adjacent the bolt-receiving openings to permit access to the bolt nuts, for the purpose described.

In testimony whereof I hereunto affix my signature.

JOSEPH ROY.
